DESIGN FOR A VELOCIPED

Harold L. van Doren, Toledo, and John G. Rideout, Perrysburg, Ohio, assignors to The American-National Company, Toledo, Ohio, a corporation of Ohio

Application October 22, 1934, Serial No. 53,723

Term of patent 7 years

To all whom it may concern:

Be it known that we, Harold L. van Doren and John G. Rideout, citizens of the United States of America, residing at Toledo and Perrysburg, in the counties of Lucas and Wood, respectively, in the State of Ohio, have invented a new, original, and ornamental Design for Velocipede, of which the following is a specification, reference being had therein to the accompanying drawing, forming a part thereof, wherein:

Figure 1 is a perspective view of a velocipede;
Figure 2 is another perspective view of the velocipede.

Figure 3 is a rear elevation of the velocipede.
We claim:

The ornamental design for a velocipede substantially as shown.

HAROLD L. VAN DOREN.
JOHN G. RIDEOUT.
